JET PROPELLED TOY

Filed Nov. 11, 1944

UNITED STATES PATENT OFFICE

2,410,682

JET PROPELLED TOY

Norval R. Richardson, Alexandria, Va.

Application November 11, 1944, Serial No. 563,023

2 Claims. (Cl. 46—95)

1

The present invention consists of a jet propeller toy, an object of which is to provide self propelled toys operable in the air, on land or in the water.

Further objects of the invention are to provide inflatable bodies of sufficient capacity to hold an appreciable supply of air, gas or like motive agent which is emitted from the body in a predetermined volume to correspondingly effect propulsion of the body at a predetermined speed; to provide a jet propelled toy vehicle, the forward speed of which is variable at the option of the user; to provide an inflatable body the contents of which are used as the propulsion agent, replenishment of the body being effected by simple means and in a facile manner to permit recharge by a child; and to provide a jet propelled toy which may be inexpensively manufactured from readily available materials.

Other objects of the invention will be apparent from the following description of the preferred forms of the invention, taken in connection with the accompanying drawing, wherein:

Figure 1 is a side elevational view of an aerial jet propulsion toy constructed in accordance with the present invention;

Figure 2 is a similar view of a jet propulsion water toy;

Figure 3 is a similar view of a jet propulsion land toy;

Figure 4 is a similar view of a toy body or tank usable in amphibious operations;

Figure 5 is a detail enlarged fragmentary view of the aft end of the vehicle body, showing to advantage the inlet valve and the outlet openings for the jet or jets;

Figure 6 is a plan view of an apertured disc for use on the aft apertured end of the body; and

Figure 7 is a modified form of disc.

In Figure 1, I have shown a jet propelled toy generally designated 8, which is of the general conformation of an airplane, the fuselage consisting of an inflatable body equipped with a cockpit 9, laterally extending wings 10 and an empennage 11. The body is preferably streamlined, the aft end thereof tapering to a truncated terminal which is provided with one or more openings 12 around which an annular recess is formed, as shown in Figure 5. The air, gas, or other content of the inflatable body is dispensed or exuded from the latter through the opening or openings 12 to provide a jet or series of jets adapted to propel the body forwardly.

I desire to control the volume of the propulsion agent escaping from the inflatable body and to

2

this end, I have in the drawing shown a disc 13 which may be provided with a single opening 14, as illustrated in Figure 6, or a plurality of selective openings 15, as illustrated in Figure 7. The disc 13 is rotatably mounted on the aft end of the body 8 in any suitable manner for certain types of toys. However, in a preferred embodiment, I employ a valved tube 16 extending through the rear end of the body and the center of the disc 13. The tube is equipped with a standard one-way valve 17 and also with external screw threads 18 for engagement with complementary threads of a pump or other inflating agent. The threads are also adapted for the reception of a nut 19 which is used to secure the disc 13 from casual displacement. Preferably the inner face of each disc is provided with a rib 20 which engages a complementary annular recess formed in the aft end of the body 8 as illustrated in Figure 5. The nut 19 normally holds the disc 13 in contiguity to the aft end of the body 8. When the body is inflated, an air seal is provided between the disc and the body, by use of any suitable sealing means. In a preferred embodiment of the invention, the rib 20, described supra, serves this purpose.

Although one opening, in the aft end of the body, in conjunction with the disc 13, is sufficient for operation, it is to be understood that more than one opening may be provided, if so desired. These openings may intermittently register with a selected opening or openings in the disc 13, to form multiple jets or sequential jets varying in volume. It is furthermore within the contemplation of this invention to dispose the walls of the openings 14 and 15 at an angle in order to vary the path of travel of the jet or jets.

Not only is it the purport of the present invention to simulate air, land, water and combination vehicles, but in addition, these toys may be equipped with the appurtenances necessary to each particular kind of travel, such as the sustaining surfaces 10 and guiding and steering means 11 of Figure 1. Where a boat is used, as shown in Figure 2, a keel 21 and rudder 22 may be employed, and the latter, being adjustable at a predetermined angle if desired. Furthermore, where a land vehicle is to be used, axially rotatable wheel 23 may be used, especially in larger and more expensive toys. With the tank body, this is also provided with the equipment necessary to adapt it for simulation in amphibious operations. It may be desired in this type of body to use a heavier and more powerful propulsion agent, introduced into the tank body

through a valved opening 24, preferably arranged at the end opposite to that which carries the perforate disc 13.

I have herein described certain preferred forms of my invention but I am aware that various changes may be made therein, within the scope of the claims hereto appended.

What I claim is:

1. A jet propelled toy including a hollow body adapted for the reception of a jet producing agent, the body being provided with a vent, a disc mounted on said body and extending over the vent to normally prevent exit of the jet producing agent, a valved tube extending through the disc and body for the charge and recharge of 10

the latter, the disc being provided with openings selectively movable into registry with the body vent.

2. A jet propelled toy including an inflatable body, the aft end of which tapers to a truncated perforate terminal, said terminal being provided with an annular recess, and a valve movably mounted on said truncated end and equipped with an extension engageable in the recess of the latter, the valve being provided with a plurality of openings selectively engageable with the perforation in the truncated end of the inflatable body.

NORVAL R. RICHARDSON.
